UNITED STATES PATENT OFFICE.

FREDERIC AUMONIER, OF LONDON, ENGLAND.

DESIGN FOR WALL-PAPER.

SPECIFICATION forming part of Design No. 22,762, dated August 29, 1893.

Application filed August 1, 1893. Serial No. 482,185. Term of patent 3½ years. Patented in England March 3, 1893, No. 208,526.

To all whom it may concern:

Be it known that I, FREDERIC AUMONIER, trading as WM. WOOLLAMS & CO., a subject of the Queen of Great Britain, and a resident of 110 High Street, near Manchester Square, London, England, have invented a new and useful Design for Wall-Paper, (patented in Great Britain on the 3d day of March, 1893, No. 208,526,) of which the following is a specification.

This design for wall paper as illustrated in the accompanying drawing, consists of acanthus and honeysuckles intermixed. The acanthus is arranged from the broader end of a

cone shaped stem having spiral flutings, and 15 is surmounted by a crossing of leaves with spread out upper part of honeysuckle leaves and flowers.

I claim—

The design for wall paper substantially as 20 herein shown and described.

FREDERIC AUMONIER.
